WATER HEATER

William F. Haddock, New Orleans, La.

Application November 30, 1939, Serial No. 306,962

3 Claims. (Cl. 122—17)

This invention relates to a water heater and has relation more particularly to an apparatus of this kind commonly known as a "storage heater," and it is an object of the invention to provide a device of this kind wherein the water is heated by heat extending both around and through the water.

It is also an object of the invention to provide a heater of this kind wherein the water is subjected to a materially large area of heat radiation thus assuring quick heating of the water.

The invention consists in the details of construction and in the combination and arrangement of the several parts of my improved water heater whereby certain important advantages are attained and the device rendered simpler, less expensive and otherwise more convenient and advantageous for use, as will be hereinafter more fully set forth.

20 The novel features of my invention will hereinafter be definitely claimed.

In order that my invention may be the better understood, I will now proceed to describe the same with reference to the accompanying drawing, wherein:

Figure 1 is a view in elevation of a water heater constructed in accordance with an embodiment of my invention;

30 Figure 2 is an enlarged vertical sectional view taken through the heater as illustrated in Figure 1 with parts in elevation and a portion broken away.

As disclosed in the accompanying drawing, 1 denotes a base member of desired dimensions and 35 which has its margin defined by an upstanding flange 2. The central portion of the member is provided with a materially large opening 3 and depending from the member 1 are the legs 4 whereby the base member 1 is supported at a 40 desired elevation above the floor or kindred supporting surface.

Mounted upon the base member 1 and in close contact with the inner face of the flange 2 is the lower end portion of an elongated casing C preferably made of sheet metal and which has disposed therearound a lamination 5 of asbestos or other heat insulating material.

This casing C is of preferred dimensions and its upper end is open but normally closed by the cap 6 resting thereon from above. This cap 6 50 may be of cast iron or other suitable material and the central portion of this cap 6 is in communication through the opening 7 with the flue 8 through which the products of combustion are 55 discharged. Resting upon the base member 1

and positioned within the casing C is an elongated and vertically disposed water tank T. The lower portion of this tank T is snugly engaged around a dome-like member 9 of cast iron or the like and which provides the combustion chamber 10. 5 In communication with this chamber 10 at the central portion of the member 9 is the lower end portion of a coil A of copper or other material readily conductive of heat.

This coil A extends to the upper end of the 10 tank T and discharges through an opening 11 at the axial center of a cap 12 closing the upper end of the tank T. This cap 12 is also preferably of cast iron while the peripheral wall 14 of the tank T is preferably of sheet metal. The opening 11 in the cap 12 is directly below the opening 7 in the cap 6 for the casing C.

The tank T is of a major diameter less than the interior diameter of the casing C whereby is provided a heating chamber 15 surrounding 20 the tank T and the lower portion of this heating chamber 15 is in communication with the combustion chamber 10 through the openings 16 disposed through the upper portion of the dome-like member 9 and the adjacent portions of the 25 tank T.

Positioned within the chamber 15 and extending from a point closely adjacent the top of the member 9 to the top of the tank T is a spiral baffle 17 to cause the products of combustion entering the chamber 15 through the openings 16 to pass upwardly around the tank T in a circuitous path thus materially facilitating the heating of the water within the tank T.

The products of combustion as they pass up 35 within the chamber 15 are discharged out through the flue but at the same time also heat the top wall of the cap 12 whereby the water within the tank T is further heated.

It is also believed to be obvious that the heat 40 or products of combustion will pass up through the coil A whereby the water within the tank T is still further heated.

Positioned within the chamber 10, in the present embodiment of my invention, is a heating unit 45 of a gas burner type. This unit 18 has leading thereto a pipe line 19 leading from a suitable source of fluid supply. Interposed in this line 19 is a conventional thermostatic valve 20 under control of the thermal element 21 extending inwardly of the tank T. As a result of the rise and fall of the temperature of the water within the tank T, the valve 20 will be automatically adjusted to regulate the required delivery of the fuel to the heating unit.

Extending down within the tank T through the caps 6 and 12 is a supply pipe 22 leading from a suitable source of water supply and terminating within the bottom portion of the tank T. Also 5 extending through the caps 6 and 12 is a carry-off pipe 23 for the heated water and which pipe terminates within the upper portion of the tank T at a point closely adjacent to the cap 12. These 10 pipe lines 22 and 23 each have interposed therein between the caps 6 and 12 a conventional coupling 24 to facilitate the installation of the heater.

From the foregoing description it is thought to be obvious that a water heater constructed in accordance with my invention is particularly well 15 adapted for use by reason of the convenience and facility with which it may be assembled and operated, and it will also be obvious that my invention is susceptible of some change and modification without departing from the principles and spirit 20 thereof and for this reason I do not wish to be understood as limiting myself to the precise arrangement and formation of the several parts herein shown in carrying out my invention in practice except as hereinafter claimed.

25 I claim:

1. A water heater comprising a base member, a casing mounted upon said base member, a tank within the casing and also mounted on the base member, a dome-like member fitted within the 30 lower portion of the tank to provide a heating chamber, means for closing the top of the casing, means for closing the top of the tank, the tank being spaced from the casing to provide a surrounding chamber and the top of the tank being 35 spaced from the top of the casing, the dome-like member and adjacent portions of the tank having openings therethrough to afford communication between the heating chamber and the chamber surrounding the tank, a spiral tube interposed between the dome-like member and the top of the 40 tank, said spiral tube being in communication with the chamber of the dome-like member and discharging within the space between the top of the tank and the top of the casing, the top of the 45 casing being provided with a flue opening, means for delivering water within the lower portion of the tank, and a discharge for the water within the tank in communication with the top portion of the tank.

50 2. A water heater comprising a base member, a casing mounted upon said base member, a tank within the casing and also mounted on the base

member, a dome-like member fitting within the lower portion of the tank to provide a heating chamber, means for closing the top of the casing, means for closing the top of the tank, the tank being spaced from the casing to provide a surrounding chamber and the top of the tank being spaced from the top of the casing, the dome-like member and adjacent portions of the tank having openings therethrough to afford communication between the heating chamber and the chamber 10 surrounding the tank, a spiral tube interposed between the dome-like member and the top of the tank, said spiral tube being in communication with the chamber of the dome-like member and discharging within the space between the top of the tank and the top of the casing, the top of the casing being provided with a flue opening, means for delivering water within the lower portion of the tank, a discharge for the water within the tank in communication with the top portion of the tank, and a spiral baffle within the chamber 15 surrounding the tank leading from the lower end portion of the tank to the upper end portion thereof.

3. A water heater comprising a base member, a casing mounted upon said base member, a tank within the casing and also mounted on the base member, a dome-like member fitting within the lower portion of the tank to provide a heating chamber, means for closing the top of the casing, 20 means for closing the top of the tank, the tank being spaced from the casing to provide a surrounding chamber and the top of the tank being spaced from the top of the casing, the dome-like member and adjacent portions of the tank having 25 openings therethrough to afford communication between the heating chamber and the chamber surrounding the tank, a spiral tube interposed between the dome-like member and the top of the tank, said spiral tube being in communication with the chamber of the dome-like member and discharging within the space between the top of the tank and the top of the casing, the top of the casing being provided with a flue opening, means for delivering water within the lower portion of the tank, a discharge for the water within the tank in communication with the top portion of the tank, the base member having an opening in communication with the chamber of the dome-like member, and a heating unit within said 30 chamber.

WILLIAM F. HADDOCK.
